UNITED STATES PATENT OFFICE.

LOUIS BLOCK, OF MAMARONECK, NEW YORK.

METHOD OF DRYING AIR.

No. 903,353.

Specification of Letters Patent. Patented Nov. 10, 1908.

Application filed November 18, 1905. Serial No. 287,945.

To all whom it may concern:

Be it known that I, LOUIS BLOCK, a citizen of the United States, residing at Mamaroneck, in the county of Westchester and State 5 of New York, have invented certain new and useful Improvements in Methods of Drying Air, of which the following is a specification.

I will describe the invention as applied to 10 removing the moisture from the air forced up through the highly resisting mass of fuel, ore, and lime, in a blast furnace, or against the strong pressure due to the "head" of melted iron in a Bessemer converter. I will 15 use the brief term "blast furnace" to mean either. The moisture thus held in what may be termed "solution" in the atmosphere is about the same per cubic foot for any given temperature, whether the pressure be great 20 or small. Thus if the air at ordinary atmospheric pressure at ordinary temperature can hold 14 grains per cubic foot and it is taken in with 10 grains, compressing such air to a tension of five atmospheres, gives it 50 grains 25 per cubic foot, which, if cooled down to its original temperature is 36 grains more than it can hold and the surplus can be deposited in the form of water. If still further cooled, so that the capacity for moisture is reduced, 30 then still more moisture will be liberated, the water, in such case usually assuming the form of snow. It is highly advantageous to have but a small and uniform quantity of moisture in the air for the blast furnace. The 35 importance of attaining this end has been long appreciated and many forms of apparatus for these purposes have been devised, some of which are in use. My improvement makes the treatment of the air highly efficient and considerably more economical 40 than any before known to me.

I have discovered that it is practicable to compress the air to a tension above that required for the blast furnace and to dispose 45 of the heat of compression by cooling such compressed air by water at ordinary temperatures, or better still by cold air after it has deposited its moisture. Such treatment takes away the heat of compression by transferring it to that cooling medium which is allowed to flow away warm. After this treatment has cooled the air in its highly compressed condition to an ordinary temperature and its surplus moisture has been con-

densed and removed, I can allow the air to 55 again expand and thereby to drive an engine which contributes to the power required to effect the compression or to do other useful work. In other words I can cause the same low-tension cold air, after it has parted with 60 its moisture in the form of water by trapping out, or of snow, by any suitable means of extracting such, to be presented in a heat exchanger to the high tension hot air before the action of the latter in the expanding en- 65 gine, and thus secure the further lowering of the temperature of the high pressure air for the removal of moisture and also the partial warming of such low-pressure air before its introduction to the stove to be 70 warmed for admission to the furnace.

I have devised means for carrying out the invention in several forms. The accompanying diagrammatic drawings form a part of this specification. I will show and 75 describe first one of the most simple.

Figure 1 is an outline view partly in vertical section, showing some of the parts of the apparatus properly connected, and Figs. 1^a and 2^a show a certain portion on a larger 80 scale. Each is an elevation partly in vertical section. Fig. 2 is a corresponding plan view showing the same with important additions, constituting the apparatus complete.

Similar letters of reference indicate like 85 parts in all the figures where they appear.

In Figs. 1 and 2 A is an air compressor of any suitable type preferably that set forth in an application for U. S. Patent made by me, refiled on the 3d of August, 1904, Serial 90 Number 219,291, driven by a steam engine D^a or other efficient means. A' is a pipe of sufficient capacity conducting the air therefrom at high tension, say 60 pounds per square inch, and at a high temperature due 95 to the compression.

B is a moderate cooler or condenser; a strong casing provided with tubes. I flow ordinary river water or well water if such can be commanded, through the spaces be- 100 tween, while the hot compressed air flows through the tubes, or I reverse these conditions; the whole purpose being to expose this air to metal of sufficient area kept at near the temperature of the cooling medium, say 35 to 90 Fah., and thus to cool the compressed air down to about that temperature. 105

Next referring to Fig. 1 alone,—B' is a

pipe carrying away the air still under its high tension and cool, but not cold. It is here shown as leading directly to the cylinder D of a motor engine analogous to a steam engine, it may be an ordinary steam engine with suitable provisions for thawing if a valve becomes clogged by ice. In this cylinder it is caused by suitably actuated valves to act alternately on the opposite side of a piston not shown and through a piston rod D', to aid in driving the compressor A or to do other useful work. This motor engine does not require specific description. The admission-valve or valves should be worked in the same manner as the corresponding parts in a good steam engine so as to cut off the supply of air when only a third or some other fraction of the stroke has been performed and thus to obtain power from the expansion as well as from the admission of the air and utilize as far as may be all the power derivable from the expansion of the air from near the high tension, say 60 lbs. per square inch by gage at which it left the compressor A too near the blast furnace tension. I will use the term furnace tension to indicate the pressure say 20 lbs. above atmosphere at which the air blown into the blast furnace through the ordinary twyers after being heated by the ordinary "stove" is able to overcome the resistance and rise through any ordinary or extraordinary mass of material in the blast furnace. D' and D² are divergent pipes controlled by valves D³ and D⁴ arranged to conduct the expanded air to snow boxes E and F, which latter may be of ordinary or suitable construction. The pressure is now down to that required to serve in the blast furnace, the furnace tension. The soft ice or snow, if any is deposited, may be alternately removed from the snow boxes, and the air pretty thoroughly rid of its moisture may be conducted by any suitable passages or vessels as the pipes E' E² and F' controlled by the valves E² F² connecting to the stove G and after being there heated flows through the twyers into the blast furnace H. Its dryness makes it economical. Its uniformity enables the iron master to deliver pig iron of more uniform quality and with less than the usual labor. The preparation of the air is attained by my method with little machinery or care. The invention is useful in this simple form.

Fig. 2 shows the invention fully developed. Here the compressing is effected at two stages. Any desired proportion, preferably more than half of the compressing is effected in the first compressor A and much heat is here developed. This is by a heat exchanger C transferred, the moderately high tension hot air coming from A and flowing onward to M giving its heat, to

the cold air at furnace tension coming by a circuitous route, from the motor D and flowing onward to the stoves.

When atmospheric air in a condition near saturation is compressed to about three atmospheres in the first compressor A its cooling while so compressed to about 60 F. in the heat exchanger C will cause much moisture to be set free in the high pressure space in the heat exchanger. Such moisture precipitated from the freely inducted and partially compressed air will be discharged through the trap C². The moderately high tension air after thus leaving part of its heat and part of its water in the heat exchanger C flows through the pipe C¹ to the second compressor M, shown as operated by a steam engine M². Here it is compressed to the final high tension assumed to be five atmospheres absolute, its temperature being again raised by the compression and is led by the pipe M¹ to a condenser B in which it is cooled by as cold water as can be obtained flowing through a liberal quantity of tubes while the air circulates through the spaces between and is cooled nearly to the temperature of the cooling water whatever that may be. More water will be liberated at this stage and will be collected and allowed to escape through the second trap B². The air at its intensely high tension, and normal temperature, say 90 F. and holding only the quantity of moisture due to such temperature, about 14 grains per cubic foot of the compressed air which is equivalent to about two and four-fifths grains per cubic foot of air under atmospheric pressure, now flows through the pipe B' to the motor D in which it is expanded and actuating a piston not shown, exerts power through the piston rod D' to actuate the first compressor A or to do other useful work.

The compressed air being allowed to expand in working through the cylinder D is lowered in pressure as in the form first described, to near that of the blast furnace, the difference being only that required to overcome the slight resistance in moving freely through the several chambers and passages interposed. This develops a lowering of temperature which may go far below the freezing point. The snow formed, if any, will accumulate in snow boxes E F and by properly operating by hand or by machine, can as in the other form be all removed. The cold air at near the furnace tension, now flows through the pipe E³ to the first heat exchanger C, where as before referred to it abstracts the heat from freshly inducted half tension air and performs two useful functions, first,—the warming of itself to require the expenditure of less heat in warming it on its introduction to the stoves G and thus to the blast furnace H, and second,—the cooling of the half-tension hot

air just being received. This air deposits its moisture in the form of water which as it accumulates in the bottom is discharged through the second trap C².

5 The high tension air holding only the moisture due to its fairly well cooled condition, is now led to the motor through the pipe B'. There is no objection to warming it again at this stage, on the contrary there 10 is a marked advantage in doing so. There is a large amount of warm water available for such use.

J' is a casing loosely inclosing the pipe B' through which the air at full tension is flowing to the motor. The water which has served to cool it in the condenser B and has in doing so become warm, is now delivered by the pipe B² into one end of this casing J and after restoring much of its heat to the 20 air in the inclosed pipe B' is discharged and allowed to flow away through the pipe J'. The warmth thus given to the high tension air in the pipe B' is of advantage by increasing the effect of its expansion in the motor and 25 also by reducing the risk of developing excess of cold in the motor.

In order to have the outflowing water of a temperature higher than that of the outflowing air, it suffices to arrange the heat exchanger in the known way for causing the temperature of the outflowing water to approximate that of the inflowing air and conversely.

Modifications may be made without departing from the principle or sacrificing the advantages of the invention.

The connections of the pipes to the several other members may be varied, and should be in case the direction of the air 40 currents require it. I can inject cold water with suitable provisions for afterward separating the water from the cooled air. Fig. 1^a shows such arrangement. This figure shows a single spray nozzle Q in a capacious 45 vessel R. There is a trap I which allows the discharge of the water without allowing the air to escape. K is a vessel analogous to a steam separator in which any entrained water is arrested and returned through the 50 pipe K' to a point below the water line in the vessel R. Fig. 2^a shows corresponding provisions with three or more spray nozzles. The number of nozzles and pipes may be varied indefinitely. In this figure there 55 are special provisions for separating the water, including a perforated platform above the level of the water and a series of pipes R² leading the water down therefrom, below the surface of the water below. By 60 this means the water is discharged without liability of being blown out even if there is a very strong current of the air. I can use the power of the motor for other purposes than aiding in the compression. I can use 65 other ordinary or suitable means for sepa-

rating and removing the soft ice or snow formed by the expansion. I describe the snow boxes as simple means which may serve. The snow boxes may be much larger than shown.

70

The invention may be operated successfully and give air which is equally uniform in its hygrometric condition and is fairly dry, by so proportioning the parts that the temperature will not, in the coolest part of 75 the circuit, the passage from the motor to the heat exchange, be but little if at all below the freezing point. In such case the snow boxes or other provision for collecting and removing the moisture in a solid or 80 semi-solid form may be omitted.

I claim as my invention:—

1. In the treatment of air for blast furnaces, the process consisting in compressing the air to a tension higher than is required 85 to force it through the furnace, cooling the so compressed air while it is under such higher tension, expanding the air to a lower but still superatmospheric tension, removing from the air its water of condensation while 90 the air is at a pressure and temperature whereat saturated air has such low content of moisture as is desirable in the air supply of a blast furnace, and supplying under appropriate pressure to the blast furnace air 95 having the so obtained low moisture content, said air being maintained under superatmospheric pressure after its said compression and cooling until it is supplied to the blast furnace, substantially as described. 100

2. In the treatment of air for blast furnaces, the process consisting in compressing the air to a tension higher than is required to force it through the furnace, cooling the so compressed air while it is under such 105 higher tension by means of water of 35 to 90 degrees Fahrenheit expanding the air to a lower but still superatmospheric tension, removing from the air its water of condensation while the air is at a pressure and temperature whereat saturated air has such low content of moisture as is desirable in the air supply of a blast furnace, and supplying under appropriate pressure to the blast furnace air having the so 110 obtained low moisture content, said air being maintained under superatmospheric pressure after its said compression and cooling until it is supplied to the blast furnace, substantially as described. 115

3. In the treatment of air for blast furnaces, the process consisting in compressing the air to a tension higher than is required to force it through the furnace, cooling the so compressed air while it is under such higher 125 tension, expanding the air to a lower but still superatmospheric tension, causing it in such expansion to perform useful work, removing from the air its water of condensation while the air is at a pressure and tem- 130

perature whereat saturated air has such low content of moisture as is desirable in the air supply of a blast furnace, and supplying under appropriate pressure to the blast furnace air having the so obtained low moisture content, said air being maintained under superatmospheric pressure after its said compression and cooling until it is supplied to the blast furnace, substantially as described.

4. In the treatment of air for blast furnaces, the process consisting in compressing the air to a tension higher than is required to force it through the furnace, cooling the so compressed air while it is under such higher tension, expanding the air to a lower but still superatmospheric tension, removing from the air its water of condensation while the air is at a pressure and temperature whereat saturated air has such low content of moisture as is desirable in the air supply of a blast furnace, heating air of the so obtained low moisture content by causing it to cool compressed air on its way to further treatment, and supplying under appropriate pressure such so heated air to the blast furnace, said air being maintained under superatmospheric pressure after its said compression and cooling until it is supplied to the blast furnace, substantially as described.

5. In the treatment of air for blast furnaces, the process consisting in compressing the air to a tension higher than is required to force it through the furnace, cooling the so compressed air while it is under such higher tension by means of an independent body of cooling medium, expanding the air to a lower but still superatmospheric tension, removing from the air its water of condensation while the air is at a pressure and temperature whereat saturated air has such low content of moisture as is desirable in the air supply of a blast furnace, heating air of the so obtained low moisture content by causing it conductively to cool compressed air on the way to be further cooled by said independent body of cooling medium, and supplying under appropriate pressure such so heated air to the blast furnace,

said air being maintained under superatmospheric pressure after its said compression and cooling until it is supplied to the blast furnace, substantially as described.

6. In the treatment of air for blast furnaces, the process consisting in compressing the air to a tension higher than is required to force it through the furnace, cooling the so compressed air while it is under such higher tension, heating the so compressed and cooled air, expanding the so heated air to a lower but still superatmospheric tension, causing it in such expansion to perform useful work, removing from the air its water of condensation while the air is at a pressure and temperature whereat saturated air has such low content of moisture as is desirable in the air supply of a blast furnace, and supplying under appropriate pressure to the blast furnace air having the so obtained low moisture content, said air being maintained under superatmospheric pressure after its said compression and cooling until it is supplied to the blast furnace, substantially as described.

7. The method of treating air for use in blast furnaces which consists in subjecting such air to a cooling operation, effecting an interchange of temperatures between the air before and after subjection to said cooling operation, heating the air that has been cooled and subjected to the interchanging operation, and passing it into the furnace.

8. The method of treating air for use in blast furnaces which consists in subjecting it to a cooling operation, then subjecting it to a further cooling operation, utilizing the temperature of such air at an earlier stage for raising the temperature of the air at a later stage, subjecting the air thus treated to a heating operation, and discharging it into the blast furnace.

Signed at the city of New York in the county of New York and State of New York this 16th day of November A. D. 1905.
